UNITED STATES PATENT OFFICE.

HENRY LOBDELL, OF TROY, NEW YORK.

CURTAIN-ROLLER ATTACHMENT.

SPECIFICATION forming part of Letters Patent No. 206,026, dated October 2, 1883.

Application filed August 15, 1883. (No model.)

To all whom it may concern:

Be it known that I, HENRY LOBDELL, a resident of the city of Troy, in the county of Rensselaer and State of New York, have invented 5 certain new and useful Improvements in Curtain-Roller Attachments; and I do hereby declare that the following is a full, clear, and exact description of the invention, that will enable others skilled in the art to which it applies 10 to make and use the same, reference being had to the accompanying drawings, and to the letters of reference marked thereon, which form a part of this specification.

Similar letters refer to similar parts in the 15 several figures therein.

My invention relates to improvements in curtain-rollers and attachments for securing curtains thereto; and it consists of a metallic strip provided with projecting points or tacks.

20 The object of my invention is to provide a convenient means for quickly and securely attaching and detaching a curtain to and from the roller.

Figure 1 is a cross-section taken at the broken 25 line *a b* in Fig. 2. Fig. 2 is a plan view of the metallic strip and curtain attached to the roller. Fig. 3 is a side elevation of the strip. Fig. 4 is a plan view of the strip as the same appears before the tacks are bent down to the position 30 shown in Fig. 3. Figs. 5, 6, 7, and 8 are cross-sections, and Fig. 9 a plan view, showing different methods of applying the metallic strip.

The difficulties of attaching curtains to their 35 rollers by means of individual tacks are well known. If the tacks are not ranged in a straight line parallel with the center of the roller, then the strain is unevenly distributed upon them when the curtain is unwound from 40 the roller in drawing it down. If the tacks are not inserted on a line at right angles to the longitudinal line of direction of the curtain, the latter will run to one side when wound upon the roller, which necessitates 45 withdrawing the tacks, readjusting the curtain upon the roller, and a reinsertion of the tacks. By having the tacks all attached to one straight strip the tacks are always kept in a straight line, they may be more quickly 50 inserted and withdrawn, and they are not

likely to be lost when the curtain is removed from the roller for washing or other purposes.

In the drawings, A represents the roller, C the metallic strip, and D the points or tacks. The tacks may be made integral with 55 the strip, which is in such cases of thin material, suitable for cutting the strips from sheet metal by means of proper dies. After the strips are cut out they present the appearance shown in Fig. 4, the points D projecting from 60 one or both sides of the strip in the same plane with it. The points are then bent downward to a position at or near a right angle to their position shown in Fig. 4, when they occupy the position shown in Figs. 1 and 2. 65

The method of attaching the curtain to the roller is as follows: The strip is laid upon one end of the curtain with the points down and in a line at right angles to the longitudinal line of direction of the curtain, when the points 70 are pressed through the curtain. The curtain is then laid upon the roller with the points in contact with it, and in a position such that the strip is parallel with the center of the roller. The points are then pressed firmly 75 into the roller, when the parts will occupy the position shown in Figs. 1 and 2.

The points or tacks D may be beveled off on their outer sides, or bent so that they will approach nearer to each other when driven into 80 the roller, as shown in Fig. 1. Although the friction of the tacks upon the roller will for ordinary use be sufficient to retain the parts in place, the strip may be further secured, when desired, by caps at the ends of the roller, 85 by rings, tacks, or one or more screws, E.

Instead of having the tacks D on the sides, they may be stuck out from the body of the strip, as shown at J, Fig. 4. They may be barbed, as shown at K in Fig. 4, to better retain the curtain during the process of attaching it to the roller. 90

The tacks D may be of any desired shape, and may be separate pieces secured to the strip in any suitable manner.

The strip may be countersunk in a groove in the surface of the roller, so that the outer surface of the strip will be flush with the circumferential surface of the roller.

I have shown in Fig. 5 my proposed method 100

of using the metallic strip with a sectional roller, in which the roller is made of two sections, A and A'. The strip C is inserted in a recess in one of the sections, with the tack D projecting therefrom. The curtain B is then laid thereon, and afterward the other section of the roller is laid upon the curtain and suitably fastened to the first-mentioned section, so that the parts occupy the positions shown.

10 In Fig. 6 the strip C is inserted in a longitudinal slot, G, in the roller shown in Fig. 7, the tacks on one side piercing the roller and the tacks on the other side projecting out from the roller. The curtain is then forced upon the projecting tacks, after which they are bent down into the recess or groove H in the roller.

15 In Fig. 8 the strip has tacks on one side only, as shown in Fig. 9. The strip is laid down flat upon the curtain, with the points in the proper places to pierce the curtain when the edge of the curtain is folded over upon the strip, and the pointed side of the strip in-

serted in a groove or recess in the roller, the points piercing the curtain and entering the roller, as shown in Fig. 8.

25

I have thus shown several methods of applying my pointed metallic strip; but I do not wish to be confined to any particular form of roller, strip, or tacks.

What I claim as new, and desire to secure 30 by Letters Patent, is—

A metallic strip provided with one or more rows of tacks fixed thereto, the rows extending longitudinally of said strip, in combination with a curtain and curtain-roller, substantially as described, and for the purposes set forth.

In testimony whereof I have hereunto set my hand this 9th day of August, 1883.

HENRY LOBDELL.
